Patented Apr. 23, 1929.

UNITED STATES PATENT OFFICE.

JOHN A. MCGREW, OF ALBANY, NEW YORK.

TIE PLATE AND RAIL FASTENER.

Application filed October 1, 1928. Serial No. 309,481.

This invention relates to rail fasteners, and more particularly to a combined tie plate and rail fastener adapted to hold the rail to the tie plate solely by the action of spring connecting means against lateral, longitudinal and vertical movements.

It is a general object of the present invention to provide a novel and improved tie plate and rail fastener.

More particularly it is an object of the invention to provide a tie plate and rail fastener comprising simple structural parts adapted to be assembled to secure a rail in position, solely by the use of a hammer.

One of the features of the invention comprises a tie plate provided with ribs thereon extending parallel to the rail base and spaced therefrom laterally, and adapted to act both as fulcrums and abutments for cantilever spring members whose opposite ends bear on the rail base and secure it to the tie plate.

Another feature of the invention comprises the arrangement of ribs on a tie plate having slots therethrough adapted to receive spring members, the slots being so directed that the inner edges of the spring members engage the upwardly sloping rail base, so that driving the spring members through the slots causes their inner ends to be lifted and the whole spring member canted to engage the walls of the slot top and bottom to cause the engaging edge to bear tightly on the rail and clamp it to the tie plate.

Other and further features and objects of the invention will be more apparent to those skilled in the art upon a consideration of the accompanying drawing and following specification, wherein is disclosed a single exemplary embodiment of the invention, with the understanding, however, that such changes may be made therein as fall within the scope of the appended claims without departing from the spirit of the invention.

In said drawing:

Figure 1 is a plan view of the tie plate and rail fastener constructed according to the present invention and shown as applied to a section of conventional railroad rail; and

Figure 2 is an end elevation thereof, showing the rail in transverse section and a portion of the tie plate and fastener in section on line 2-2 of Fig. 1.

The present invention relates to a device

for securing a railroad rail to a tie. Any conventional form of tie may be used, and the device provides a suitable tie plate such as is customary in high grade track construction to distribute the bearing stresses of the rail over a larger area of the tie. It likewise provides means for attaching the rail to the tie plate independent of the means for securing the tie plate to the tie, so that it is not necessary to remove the fasteners in the tie when changes in gauge or similar adjustments are made, and therefore the life of the tie is materially lengthened, particularly where it is formed of wood, because the tie fibers are not broken or crushed by driving fastening members in new positions.

Referring to the drawing, a section of conventional rail is shown at 10 having the base 11 provided with an outwardly and downwardly sloping surface 12 at each side of the center thereof. The rail is adapted to rest on a tie plate 13 composed of a rectangle of suitable metal preferably rolled to the form shown. Its central portion is thicker and provides on its upper surface a face 14 to receive the bottom of the rail base. The thinner ends 15 are perforated as at 16 for the passage of suitable fastening means such as spikes or lag bolts.

Formed integral with the tie plate and extending longitudinally of the rail, are the ribs 17, one on each side of and somewhat spaced from the base of the rail, as shown, so that the rail is free to be adjusted laterally of the tie plate without moving this plate. These ribs project upwardly and are slightly inclined toward each other, as clearly shown in Fig. 2. Each rib is provided at the center of its length with a transverse slot or passage 18, the walls of which are substantially normal to the surface of the rib which they intersect. In general it may be said that the bottom wall of this slot is about the same height from the surface 14 as is the lowest portion of the upper surface of the rail base, i. e. at 19.

Cooperating with each rib and passing through the slot therein is a key or spring plate 20, generally of rectangular formation, as shown in Fig. 1, and of a uniform thickness somewhat less than the height of the slot 18. The plate is likewise narrower than the total length of the slot, so that it may be freely passed through the slot. The inner edge 21 of the spring plate is prefer-

ably rounded as shown while the outer edge may be left square. Due to the inclination of the rib and therefore of the slot, when a spring plate is passed through the slot it is forced to take a downward inclination toward the rail, so that its inner edge 21 engages the sloping surface of the rail base as at 22 in Fig. 2. Continued movement of the spring plate toward the web of the rail causes this edge 21 to rise along the inclined surface of the rail base until the upper surface 23 of the spring plate engages against the edge 24 of the slot, and the bottom wall 25 of the spring plate engages against the edge 26 of the slot. This edge 24 being at the inner face of the rib and at the upper surface of the slot forms a fulcrum between the bearing line 22 on the rail base and the abutment or support 26 at the junction of the outer face of the rib and the bottom wall of the groove. Thus, the spring plate or key acts as a cantilever supported in the rib and carrying as a load its pressure on the rail base. This "load" may be increased by driving the key inwardly so that its edge 21 rises more on the rail base and causes the whole plate to flex about the fulcrum 24. The plate is made from highly tempered spring steel so that it will not receive a permanent set due to this flexing, and thus always has a reserve resiliency to provide a pressure on the rail base which retains it against the tie plate and secures it against movement.

35 Lateral adjustment of the rail for the purpose of gauging the track can be accomplished by driving one key further than the other or by setting the rail in the desired position and driving both keys together. It 40 may likewise be accomplished by temporarily blocking the rail from the inner faces of the ribs in the desired position and then driving up the keys.

It will be noted that when the keys are 45 driven up tight so as to apply a continual spring pressure on the rail base, that the fulcrum edge 24 has a tendency to bite into the key in the manner of the conventional slit lock washer which effectually prevents 50 the key from slipping out of position in addition, of course, to the locking action resulting from it being canted in the slot. Thus vibrations and pounding resulting 55 from the passage of wheels over the rail will not impair the holding action of the fastening means.

The form of tie plate shown is extremely simple to make, so that quantity production is materially simplified. It can be 60 rolled in the customary manner and cut into convenient lengths, which are then slotted.

Having thus described the invention, what is claimed as new and desired to be secured by Letters Patent is:

65 1. In a rail fastener, in combination, a tie

plate, an integral rib extending above said tie plate and longitudinally of the rail base thereon, a slot through said rib transverse to said base and a spring key driven through said slot and bearing only on said base and 70 in said rib to retain the rail in position on said tie plate.

2. In a rail fastener, in combination, a tie plate adapted to receive a rail base, a rib on each side of said base, parallel thereto 75 and integral with said tie plate, a slot in each rib extending lengthwise thereof and sloping downwardly toward said base, a key of spring material thinner than the width of said slot, passing through each slot and 80 having an edge resting on the sloping rail base whereby movement of the key toward the rail elevates the end on the base and binds the key in the slot.

3. In a rail fastener, in combination, a tie plate adapted to receive a rail base thereon, a rib on each side of said base spaced therefrom, a pair of spring keys each having an edge resting on the sloping upper surface of said base, means on each rib forming a 90 fulcrum for its key and means on each rib forming an abutment for its key whereby driving said key toward the rail web raises the edge thereof on said base and flexes the key about said fulcrum. 95

4. In a rail fastener, in combination, a tie plate adapted to receive a rail base, a spring key adapted to be driven laterally of said rail over the base thereof and means on said tie plate having an opening the edges of 100 which form a cantilever support for said key.

5. In a rail fastener, in combination, a tie plate adapted to receive a rail base, a pair of spring keys adapted to be driven laterally 105 of said rail over the base thereof and means on said tie plate having openings the edges of which form cantilever supports for each key, said means permitting movement of said keys laterally of the rail to tighten their grip 110 on said base.

6. In a rail fastener, in combination, a tie plate, a rail base on said plate having its edges free, a spring key for each side of said base, means restraining each key from rotation away from said base, said means permitting movement of said keys over said base to engage the sloping surface thereof to clamp the base to the tie plate, said means having a portion to bite into said keys to 120 prevent slipping.

7. In a rail fastener, in combination, a tie plate adapted to be secured to a tie, a rail base receiving surface on said plate, a rib extending parallel to the rail base, integral 125 with the tie plate and inclined toward the rail, a slot through said rib normal to the face thereof and parallel to the tie plate and a spring plate thinner than the width of said slot passing therethrough and hav- 130

ing an edge engaging the sloping surface of the rail base.

8. In a rail fastener, in combination, a tie plate adapted to be secured to a tie, a rail base receiving surface on said plate wider than the rail base, a rib on said tie plate on each side of the rail base and spaced therefrom, a spring plate in lateral sliding

engagement with each rib and means on each spring plate to engage over the sloping surface of said rail base and clamp said base to said tie plate. 10

In testimony whereof I hereunto affix my signature.

JOHN A. McGREW.
